Fig. 1

Fig. 2

Fig. 3

FIG. 1 is a side elevational view of a base for holding bottles or the like showing our new design, a portion thereof being broken away to reveal a section through the center thereof;

FIG. 2 is a top plan view thereof; and

FIG. 3 is a bottom plan view thereof.

The design is circular and symmetrical so the other elevation views can be understood from the views on the drawing. The portion broken away in FIG. 1 is identical to that shown at the bottom left of FIG. 1.

We claim:

The ornamental design for a base for holding bottles or the like, as shown and described.
